UNITED STATES PATENT OFFICE

THORVALD J. JORGENSEN, OF FRANKLIN SQUARE, AND OLAF K. JORGENSEN, OF GARDEN CITY, NEW YORK

SLED

Application filed February 28, 1931. Serial No. 519,033.

This invention relates to new and useful improvements in sleds, and has for one of its objects the provision of a vehicle of the kind described, wherein the constituent elements are so coordinated structurally as to assure improved results with material which is easy to manufacture, and which is also easy to maintain in efficient working condition.

Another object of the invention is the provision of a sled wherein relatively movable body and runners are so arranged that the latter, while rigid for fore and aft movement, are yieldable vertically, in order to resiliently support the weight of the load carried, particularly while the vehicle travels over obstructions or an uneven course.

A further object of the invention is the provision of steering means, which, having a pivoted runner and a movable post to carry the same, also include a control device for the post, so that the latter may be set for predetermined movement, at least in one direction, or to guide the vehicle on a straight course.

With the above and other objects in view, this invention consists of the novel features of construction, combination and arrangements of parts, hereinafter fully described, claimed and illustrated in the accompanying drawing forming part of this specification, and in which similar characters of reference indicate corresponding parts in all views, and in which:

Figure 1 is a lateral elevational view of our improved sled;

Figure 2 is a front elevation;

Figure 3 is a top plan view;

Figure 4 is an enlarged sectional detail view taken on the line 4—4 of Figure 3; and

Figure 5 is an enlarged section, taken on the line 5—5 of Figure 1.

Referring more particularly to the drawing by reference characters, 10 designates a body, preferably of wood, which may be made in two attachable sections 11 and 12, for economy of material.

The body 10 is provided with a seat 13, which may have supports, as at 14, and with a foot board or rest 15.

Attached as by screws 16 to the body 10 is

a pair of hinge plates 17, 18; and to a steering post 19, by like screws 20, is attached a pair of mating hinge plates 21, 22, so that on operation of a handle bar 23 of the post the latter is swingable about the axis of pins 24 of the hinges for changing the position of the runner 25 to direct the movement of the sled. This runner is pivoted at 26 for movement in a vertical plane to yieldably meet obstructions.

A rear runner includes a pair of like members 27, which are attached by a tie bar 28, and on this bar are fixedly mounted the lower plates of hinges 29, 30, the upper plates of which are rigidly carried by a cross-bar 31 of the body 10. Like lateral supports 32 additionally hold this crossbar rigid with the section 11.

In the normal travelling position, as shown, the bars 28 and 31 are forwardly spaced apart, so that as a runner 27 meets an obstacle said runner tends to move upwardly about the pivot pins of the hinges 29, 30. A plate 33 is centrally attached to the bar 31 by screws 31', or the like, and the bar 28 has an aperture 34 therein.

Said plate is provided with a rigid arcuate strut or support 35, and to the bar 28 is fastened a leaf or plate spring 36, the forward free end of which movably contacts with the lower terminal of the strut. Said spring therefore opposes upward movement of the forward end of the runner, thereby resiliently taking the force of the impact of the runner with an obstacle, as aforesaid, instead of transferring the force directly to the body 10.

The result is that the vehicle is rendered comfortable and safe for travel. Two cushioning springs 36 and struts 35 may be used in which case the same may be positioned adjacent the ends of the bars 28, 31, instead of centrally.

In order to lock the steering gear in a selected position, preferably for straight line travel, we provide a manipulable locking rod or bar 37, which is slidably positioned in a duct or passage 38 of the body 10.

This latter bar is, in the present instance, threaded; and threadedly mounted on the 100

bar is a manipulating knob or cylinder 39, which is positioned in a suitable large aperture 40 of the said body. The locking bar is provided with an elongate groove 41, and the 5 post 19 has therein a recess 42, which is aligned with the duct 38 when the runner 25 is directed for straight forward movement.

The wall of the body has therein a pin 43, the inner terminal of which is loosely positioned in the said groove.

On revolving the knob 39 the bar 37 is therefore slideable longitudinally in its duct for performing the locking or unlocking operation.

15 The runners have protective metal strips 44 thereon, and the device may be rendered more attractive by painting or otherwise finishing the same in selected colors.

It is obvious that changes may be made in 20 the form, construction and arrangement of the several parts, as shown, within the scope of the appended claims, without departing from the spirit of the invention, and we do not, therefore, limit ourselves to the construction and arrangement shown and described 25 herein.

What we claim as new, and desire to secure by Letters Patent of the United States, is:

1. A sled, comprising a body having a support therebelow, a runner having an aperture therein for movably receiving said support, and spring means mounted on said runner below its aperture for carrying part of the weight of said body, said spring being in contact with said support.

2. A sled, comprising in combination with a body, an elongate support having one of its ends depending below said body, means attaching the other end of said support to said body, a runner having therein an aperture wherein said first end is movably positioned, and spring means carried by said runner below its aperture, said means contacting with said first end to resiliently absorb weight 45 of the said body.

3. A sled, comprising in combination with a body and a relatively movable runner, which latter is provided with an aperture, hinge means, including a pivot, mounted on said body and on said runner, an elongate support curved on an arc having its center on said pivot and attached at one end to the body, and spring means carried by said runner and disposed therebelow for urging said support 55 to carry part of the weight of said body, the other end of said support being movably disposed in said aperture.

4. In a sled comprising a body and having relatively movable steering post, control 60 means for said post, which latter is provided with a recess, said body having therein a duct and an aperture, said means having a threaded rod slidably mounted in said duct and partly movable into said recess whereby to 65 lock said post against movement, said rod

having a longitudinally disposed groove therein, manipulable means disposed in said aperture and revolvably mounted on said rod, and a pin carried by said body and partly disposed in said groove to hold said rod against turning movement during revolution of said manipulable means.

Signed at New York city, in the county of New York and State of New York this 6th day of January A. D. 1931.
